2,439,602

INSULATING CONFINED SPACES

Clark C. Heritage, Cloquet, Minn., assignor to
Wood Conversion Company, Cloquet, Minn., a
corporation of Delaware

Application March 2, 1943, Serial No. 477,753.

5 Claims. (Cl. 20—101)

1

The present invention relates to the placement of particles of thermal insulating material to build up a thermally insulating integrated mass of such material in a confined space. In particular it relates to carrying the material in a gaseous vehicle (hereinafter referred to as air) to a deposited growing mass of such particles formed by deposition of particles from the vehicle.

In its general aspect the invention contemplates completely confining a space to be so filled with insulation material, whereby to define the form of the mass to be produced. The space may be provided substantially completely by or within existing articles. However, as required or desired for the purposes of the invention, the space to be filled is completely defined by bounding facial walls having essentially some filtering area for exhausting the gas in which particles of the insulating material are introduced, and having essentially in the area of the confining walls, one or more inlet areas for introducing the gas containing the particles, each such inlet area being essentially in and a fraction of a confining wall or face in a manner analogous to the relation of the area of a pouring sprue in molds for casting metal articles to a space-defining area of the mold.

It is also a general aspect of the invention that the particles of insulating material are such as may be consolidated into a gas-filtering body, when in finally deposited form, whereby in conducting and completing the introduction, gas entering the space through inlet area may pass through all or a part of the body as required to exhaust through filtering area.

Another general aspect of the invention permits the form of the space to be complex, or angular, and not limited to panel-form spaces. Thus, the vehicular stream of gas is introduced at a differential pressure, relative to the pressures at inlet area and at filtering area, and at such a velocity that the particles suspended in the gas are carried with turbulence inside the space to all portions of the space remote from inlet area, and that the differential pressure packs the deposited mass to a consolidated body filling the space while said pressure of the gas stream is maintained to and, if desired, even after the complete filling of the space.

The invention is applicable in many fields, for example, in packing fiber or other insulating material into carboys to protect and insulate the flasks of liquid therein. However, its presently preferred use is in insulating the doors and cabinets of refrigerators, such as are used in homes.

2

In the field of artificial refrigeration, high standards for insulation in domestic and other refrigerators have developed in order to minimize heat loss, because high heat loss adds to the cost of operation. Considerable difficulty has been encountered in the commercial development of refrigerator insulation in parallel with the development of domestic artificial refrigeration. Along with high standards and for low heat loss, low cost of insulating material and of insulating process are important, as are uniformity in each cabinet, and uniformity from cabinet to cabinet in a production line.

In addition, there is the problem of permanence, in which resistance to settling of packed bulk insulation is most important. Such resistance can be attained by increasing the density of packing, with which heat leak or heat conductance increases, as a general rule, in the range encountered in refrigerators. It is, therefore, important to minimize density, consistently with acceptable resistance to settling and acceptable insulating value. All these factors lead to a need for a process which is subject to control for meeting them.

In the prior art there has been no low-cost process for packing a specified material uniformly and integrally into a cabinet, and uniformly from cabinet to cabinet in a production line. The present invention provides such a process, and so used it gives reproducible results with any reproducible material. Vegetable fibers such as from wood may readily be produced from time to time with reproducible properties within given specifications, and with such material and with the present invention, a low-cost process for uniformly and efficiently insulating spaces, such as those in refrigerators, becomes available to the manufacturers of refrigerators. Reference is made to my copending application Serial No. 336,495, filed May 22, 1940, now Patent No. 2,325,055, issued July 7, 1943, describing reproducible fibers, which are useful as particles for practice of the present invention.

The present application is one of a series of my cofiled applications Serial Nos. 477,751; 477,752; 477,753; 477,754 and 477,755, each one of the series being directed generically and specifically to a distinct species disclosed in my said original application Serial No. 294,212.

It is the object of the present invention to insulate interior walls of a body providing an opening, by confining the space to be insulated in part by means of a removable fixture containing either one or both of inlet area and filtering area, and

introducing into said space through inlet area a stream of gas carrying particles of insulating material, then removing the fixture.

It is also an object to provide only a single inlet area in the said fixture.

It is also an object to provide all the filtering area and all the inlet area in the said fixture.

It is a particular object to insulate refrigerator cabinets having a food compartment by providing such a fixture which is in part a dummy for the food compartment, then insulating the space between the said dummy and the cabinet, then removing the fixture and replacing it with the food compartment.

Various other and ancillary objects and advantages of the invention will appear from the following description and explanation of the invention given with reference to the accompanying drawings in which:

Fig. 1 represents in perspective half of a refrigerator cabinet and above it in perspective half of a food compartment in position to be dropped into place in the cabinet;

Fig. 2 represents in two parts a dummy for the food compartment, as a box-like fixture and a pipe system which belongs within the said fixture, the base being shown separated for convenience in illustration;

Fig. 3 represents the type of blower and feeding means therefor which is used for connection to the fixture of Fig. 2;

Fig. 4 represents a modified fixture as a dummy food compartment, having but one inlet conduit and having differently arranged filtering areas, one wall of the fixture being shown rectified to the plane of the bottom merely to facilitate the illustration;

Fig. 5 represents in perspective a portion of the refrigerator cabinet of Fig. 1 filled with insulating fiber by use of the fixture of Fig. 4;

Fig. 6 is a fragmentary view in cross-section taken on the line 6—6 of Fig. 4 and Fig. 5, when the fixture of Fig. 4 is in operating position within the cabinet;

Fig. 7 is a view in perspective and vertical cross-section of an inverted carboy casing with its bottom removed and with a fixture inserted therein; and

Fig. 8 is a vertical cross-section of the same carboy in completed form after filling the casing with insulating material, after removal of the fixture, and after replacing the fixture by the bottle.

In my earlier parent application Serial No. 294,212, the process is described generically and specifically with respect to various forms of the space to be filled, and various types of space-confining walls, and removable fixtures, having particular reference to variations in the process for insulating domestic type refrigerators. These variations include filling a refrigerator in which the food compartment is already mounted, and also in which the food compartment is not mounted. In the latter case, a fixture in the form of a dummy for the food compartment is employed, and the fixture is used to provide filtering area, and may be used to provide inlet area. The process is flexible for accommodating it to various types of refrigerators, as well as various types of spaces not necessarily those of refrigerators. In the said earlier application, there is claimed specifically a method of filling a refrigerator in which the food compartment is mounted, both the cabinet and the food compartment having openings therein for accommodating the insertion into the

food compartment of a refrigerating unit. One of the said openings to the space is used for introducing the gas, while the other is blocked off. The open space at the door opening between the cabinet and the food compartment, where breaker-strip material is located in the completed refrigerator, is closed by a fixture or closure provided with filtering area, and preferably including also some imperforate area. Thus, the gas introduced passes through the gas-filtering body of insulating material built up in the space. Then the fixture is removed, and breaker strip used to close the gap. The space between the openings for the unit thus has insulation, which may be disturbed as necessary in making connections when installing the refrigerating unit.

It is also set forth that the stream is introduced at a differential pressure between inlet and filter areas. This may be effected by having atmospheric pressure at either the inlet area, or at the filtering area. The latter is preferred for many practical and mechanical reasons.

In the present application it is likewise intended that the pressure be a differential one, but to simplify the description and the illustration, only the preferred one of super-atmospheric pressure at inlet area is specifically described and illustrated without intention to limit the invention thereto.

After the introduction of the insulating material into the space to be insulated, especially in a refrigerator, there are numerous mechanical operations which may be necessary to complete the article for use or sale. However, these form no essential part of the invention, and detailed description and illustration of them are herein omitted.

The preferred closures or other means having filtering area are preferably permanent fixtures used in a production line, and are in preferred practice removed after each use. However, these may be of other structure, for example, metal or cloth filters of such character that they need not be removed. When retained, they may be a permanent part of the final structure, covered or not. Hence, the removal of such closures is not considered an essential part of the process. But in certain cases it may be included as an essential part of certain aspects or variations of the invention.

The present invention may be used for fibers, flakes and particles of other forms. Examples of fibers are hair, wood fiber, vegetable fiber, kapok, mineral wool, glass wool, asbestos, straw, grasses and many others. Examples of other materials are flaked paper, exfoliated vermiculite, mica, ground cork and like materials. Fibers are preferred, because they mat and felt and produce stable forms in more complex variations of the invention where fixtures may be used and removed. The following illustrations are, therefore, given with respect to wood fiber, such as that according to my said copending application Serial No. 336,495, filed May 22, 1940, now Patent No. 2,325,055, issued July 7, 1943, which was developed primarily for use in the present invention.

The invention involves the building up of a consolidated gas-filtering body of particles of insulating material introduced as suspended matter in a stream of gas, into a confined space to be insulated; and it involves the provision in the confining walls of said space of filtering area to retain the particles and exhaust the gas. The location of inlet area, the number of inlet areas,

and the location, size and number of filtering areas are not critical with respect to any given space. This is because the stream of gas is introduced at a velocity to impel the particles with turbulence into the space and to all parts of the space. The greater the shortest distance from inlet area to filtering area, the thicker is the body of insulating material through which gas must pass to exhaust. Therefore, for practical convenience, it is desirable to have filtering area close to, or even adjacent to inlet area. Experience has shown that because of the turbulence, the particles may deposit in regions some of which are adjacent to filtering area, and others of which are remote from both inlet area and filtering area. The resulting deposit grows toward the inlet area, and to or through the inlet area. In such case, the filtering area close to or adjacent inlet area facilitates the deposition of the last-deposited material. The conditions establish a complexity of air currents which change as the remaining space to be filled changes. Cyclonic currents have been observed which tend to throw carried particles centrifugally out of the local air stream and deposit them by centrifugal force and in the manner described. Also direct deposition by filtration has been observed as one of the resulting actions to deposit the introduced particles.

In Fig. 1 there is illustrated a refrigerator cabinet and a food compartment therefor lifted out of said cabinet. The cabinet comprises a box-like steel form 10 having a back 11, shown in horizontal position, but normally being vertical, two refrigerator sides 12, refrigerator top 13, cabinet bottom 14, and a supporting housing 18 in which machinery may be located. The panels 11, 12, 13 and 14 provide a cabinet space with opening for closure by a refrigerator door (not shown). This opening in the cabinet presents an internal flange 15 with a lip 15'. In the back wall 11 is an opening 16 for use in connection with a refrigerating unit, not shown. The opening is closed in the illustration by reason of the cabinet resting on platform 17.

The food compartment is generally designated 20. It has a back panel 21, sides 22, top 23, bottom 24; an opening 25 in the back panel for use in connection with a refrigerating unit to be inserted in the food compartment. The food compartment is of a size to fit within the flange 15 of the cabinet. The lip 15' receives screws by which breaker strip material is secured to it, and to the walls of the food compartment, at the top thereof, to close a gap between them. This provides space all around the food compartment to receive insulation, which space also has a box-like form.

According to the present invention, the food compartment is not within the cabinet when the insulation is placed. Rather, there is provided a fixture which is a substantial dummy for the food compartment with respect to the faces of the food compartment which are to contact the insulation. Preferably, the likeness is exact, but if it deviates, it is preferred that the dummy provide thicker space than is provided by the food compartment, whereby the food compartment can compress the deposited insulation. However, the dummy may be larger in these respects, in the cases where the deposited mass expands slightly upon removal of the dummy. Such expansion occurs with deposited wood fiber, and it is greatest if removal of the dummy occurs immediately after deposition. If the wood

fiber is allowed to stand in the compressed state of original deposition, the initial elasticity to expand is to a large degree lost by rearrangement of the fibers into a more thoroughly felted form.

In the present description it is considered that the dummy is the same size as the food compartment in the said respects, merely to simplify the structures to be illustrated.

Fig. 2 shows such a dummy fixture, described in my earlier parent application Serial No. 294,212. As therein described, it was designed for use in a refrigerator cabinet at either top or bottom of which there was not space to be insulated adjacent the food compartment. Hence, one illustrated wall of the fixture is shown as imperforate. It has been used in a refrigerator where the insulation above the food compartment is solid board, as of fiber or cork, to give support to heavy mechanism located above it in the cabinet body. However, such a fixture is also useful where there is space adjacent such imperforate fixture wall to be insulated by the present invention. The process is such that the material will deposit behind all the walls of the illustrated fixture, so long as there is inlet area and filtering area in the walls confining the whole space to be insulated.

In Fig. 2 there is represented a box-like fixture 30 which in form is a substitute for the food compartment 20 to define the same insulating spaces inside the cabinet 10, between the walls of the fixture and the walls of the cabinet. The walls of the fixture are designated: end 31, end 32, bottom 33, and sides 34 and 35. The panels 33, 34, and 35 have two inlet areas, respectively 36 and 37, 38 and 39, and 40 and 41. The end panel 32 has one inlet opening 42. A complex unitary pipe fixture is shown in perspective in Fig. 2, which is illustrated as removed from the box fixture 30, of which it is actually a part built into it. The pipe fixture has a main feed line 43, for example, of 4-inch diameter sheet metal pipe, with 3-inch diameter take-offs designated by numerals already assigned to the feed openings. Either end or both ends of the main feed line 43 may be used to admit air carrying insulating material. One end 44 is shown as closed.

Each panel has a closed or imperforate peripheral area forming a frame, and the frame opening may be screened, except where there is a feed opening or inlet area. In detail the panels, all except panel 31, have screen areas of wire cloth 45. In the actual construction, the ends of the feed pipes are secured to the screens, for attachment to a fiber-air supply, and for removal from the integral felted jacket formed about it in the cabinet.

When the fixture is withdrawn, the peripheral space is filled with a box-like unitary mat or body which is self-supporting with the fixture withdrawn. With simple precautions the food compartment is then inserted and secured in final position.

The following illustrates means for blowing particles to the fixture. Consider the apparatus of Fig. 3, having a fan-type blower 45. It has a conduit 46 for entry of air, into which fiber may be fed by hand, or by a mechanical device, such as a picker, or a worm screw 46a. The fan discharges downwardly through conduit 47, to which suitable connection is made.

Consider the apparatus of Fig. 3, when the pipe 47 is six inches in diameter and connected to a space to be filled. The fan is operated at 3740

R. P. M. by a 15 H. P. motor of 1800 R. P. M. Running idle, (connected and operated but no fiber fed), the measured pressures are as follows:

Table I

In pipe 47	Pressure in inches of water
Lateral (static) pressure.....	8.5
Total pressure.....	10.25
Velocity pressure.....	1.75
Velocity.....	5300 ft. per minute.
Output.....	1040 cu. ft. per minute.

The blowing system was used to fill a space $\frac{1}{4}$ full, then again to $\frac{1}{2}$ full, then to $\frac{3}{4}$ full, and then to 100% full, with measurements of the system (idle) at each stage. The measured values are combined in Table II with values taken from Table I and are in the same units as those in Table I.

Table II

Measured in pipe 47	Empty	$\frac{1}{4}$ full	$\frac{1}{2}$ full	$\frac{3}{4}$ full	Full
Static pressure.....	8.5	12	12	13.5	14.75
Total pressure.....	10.25	13	13	13.5	14.75
Velocity pressure.....	1.75	1	1	1	1
Velocity.....	5300	4006	4006	4006	4006
Output.....	1040	785	785	785	785

It is noted that under conditions where the exit is wholly or to a degree blocked, as when the space is full, there is a "back pressure" encountered at the inlet to the centrifugal fan.

The back-pressure is an important feature of the use of super-atmospheric pressure feed, with apparatus permitting back pressure. Consider in Fig. 3, that the fan may run while the feed line 47 is open. A momentum is established into pipe 47. As this is blocked off, the moving stream is retarded, at first in part, and fiber gradually fills up the inlet conduits. A window (later described) indicates this and the process may be stopped. If not stopped, the back pressure at the inlet blows fiber back in pipe 46. Thus, fiber fed into the inlet will also be blown out the inlet. The appearance of back-feed or back-pressure is an indication of the final status of being filled.

Many factors influence the result, and practically it is necessary to arrive at standard conditions for the particular equipment used, and the job at hand. For example, it has been found to be a general rule that the faster the fiber is fed, the less the density of the mat obtained. However, this rule is limited to a very short period of time. In one tested instance the feeding time for the space was varied from fractions of a minute to several minutes. The curve of density has been plotted vertically against feeding time plotted horizontally. The curve rises rapidly, and at about 25 seconds it begins to flatten out. In about 60 seconds it has reached a maximum density. Such curves were obtained with different fan speeds, and it was found that high speeds (greater kinetic energy to fiber) at the same feeding time gave higher density mats. By constructing such curves from experimental procedure, the conditions for most efficient operation and for uniform operation may be easily determined.

Fig. 4 represents a second and a preferred form of fixture in which both inlet area and filtering area are more limited, and imperforate area is more extensive. Simplicity of fixture structure is evident, and filtering area is arranged with

respect to the more limited inlet area, to secure good formation and stability of the deposit, when of wood fibers, against collapsing on removal of the fixture.

Fixture of Fig. 4 has 5 panels, including bottom 50, and two short sides 51 and 52 and two long sides 53 and 54. The inlet area 55 is in the central part of bottom 50, and is connected to fiber-air conduit 56. At the corners of the bottom are small triangular filtering areas 57 of screen wire. Each of the fixture side walls has like triangular filtering areas 58 of screen wire adjacent the areas 57. At the top of the side walls of the fixture are disposed near each corner narrow horizontally elongated screen areas 59. On the longer side walls 53 and 54, there are in the vicinity of the center, two narrow vertically elongated filtering areas 60 and 61, spaced apart. The function of these is to vary the fiber formation from that which would result from omission of the areas 60 and 61, whereby a reinforcing formation occurs. This is described in the copending application of Pauley, Serial No. 439,678, filed April 20, 1942, wherein the same fixture is illustrated and specifically claimed. A window 56a is shown in the conduit 56 to indicate over-filling by the appearance of packed fiber at the window.

Fig. 5 illustrates the nature of the fiber deposit formed in the cabinet 10, using the fixture of Fig. 4. The areas formed adjacent filtering area are shown by stippling, except the areas formed adjacent screens 60 and 61. The latter areas in the mat are designated 61 and 62. Screen areas 60 and 61 tend, as do other screen areas, to cause the deposit to grow away from them, and they also cause an accumulation of fines to act as reinforcement. The lines of growth give a grain to the deposit and by mixing the grain by coaction of the horizontal and vertical areas illustrated, the vertical walls of large area in the final deposit are stronger and do not collapse.

Fig. 6 is a fragmentary section on line 6-6 of Figs. 4 and 5, showing the wall 10 of the cabinet, screen 60 of the fixture, imperforate side wall 54 of the fixture, and fiber 62 heterogeneously arranged and more compact adjacent screen area 60, and a grain extending away therefrom, the drawing being indicative rather than exact.

Filtering area is not essentially limited to a removable fixture, in practicing the invention, and may be located anywhere in the total area confining the space. Thus, in Fig. 1, a hole 28 in wall 14 for connections to the refrigerating unit may be temporarily covered by screen 29.

A possible modification of the process is to use the fixture Fig. 4 with the inlet area thereof blocked off or removed, and replaced by inlet area on the cabinet. Where there is an opening 16 in the cabinet, which in Fig. 1 is shown as closed by the platform 17 beneath it, there may be an inlet opening provided in the platform. The opening 16 may be placed over this inlet area in the platform. The results will be the same, since it is immaterial in which direction the air stream moves as it enters the back panel space between the back walls of the cabinet and the fixture.

The invention is not limited to refrigerators and has numerous applications wherein dummy fixtures may be employed. Figs. 6 and 7 illustrate but one of these different fields. In Fig. 7 the box 70 illustrates the casing of a carboy in inverted position, with the bottom removed, on which bottom a flask or bottle normally rests. There is shown in the box, a unitary fixture 71 which is substantially a dummy for the major

part of the bottle. It has a cylindrical body portion 72, shoulders 73 and "neck" 74, and an external flange 75 fitting the casing and located at the level for the bottom of the bottle. At the region where the flange joins the body, there are 5 a plurality of wire screens 76 forming filtering area. At the center is a conduit 77 secured by braces 78 to the body 72. The conduit branches into two parts 79 and 80 which terminate at inlet areas 81 and 82 in the vicinity of the shoulders 73.

In use a stream of air in which fiber or the like is suspended is blown in via conduit 77, at a high velocity creating a turbulence of air and particles in the confined space, and carrying particles to all portions of the space. Particles pack 15 against the filters 76 and a deposit grows, filling all the space at least to the inlet areas 81 and 82, and even into the conduit if blowing is continued. The fiber or other body is designated 83.

Then the fixture 71 is withdrawn (see Fig. 8), 20 exposing hole 85 in the casing (normal top), which hole is large enough to receive the mouth 86 of bottle 87, which is shown in position replacing the removed fixture 71. Then means is inserted which spaces the bottle laterally from the casing sides and from the casing floor. Preferably, this spacer as to the casing floor is insulating and cushioning, and a thick pad, or fiber board 88 is suitable. Blocks of wood, fiber board, or other material, 89, for lateral spacing, may be suitably secured in the casing, as by being mounted to the board 88. Then the floor 90 of the casing is secured in position.

It is pointed out that, if the space occupied by the fiber board 88 were by some modification of the process blown to a density of the indicated mass 83, it would be subject to compression by the weight of the filled bottle in upright position. Dropping of the bottle from this cause would affect the packing 83 in the vicinity of the shoulders of the bottle.

Although I have shown all the inlet area located in the various fixtures illustrated, it is to be understood that this is only the preferred practice. Inlet area to the space may be one or more areas and be located anywhere in the walls, and the same is true of filtering area; but in order that the fixture may have a function for the process, either inlet area or filtering area is provided in the fixture, preferably both, and preferably all the inlet area and all the filtering area.

The use of a fan is preferred for the reason that it is a means of unfelting the fibers to substantially individual fibers. It is this form which gives the best results. However, broadly, the fibers need not be completely unfelted, and may be in clusters or small aggregates. Use of other means, such as vacuum on the screen end, or feeding fiber directly into a current of air, is conducive to providing such loose aggregates, rather than individual particles of fiber. The important point is that these are not under mechanical pressure to felt them, and they tend to unfelt in process.

The terms "screening means" and "filtering area" as used herein or in the claims refer to an area with any effective lattice or perforated member which acts as a screen to filter particles from the carrying gas, and it is to be distinguished from a member porous to air and from a crack or an elongated slot.

The location and size of filtering area relative to inlet area, and the velocity of the stream of gas, are all such that particles are introduced 75

with turbulence in all portions of the space to be filled, and pack therein.

Numerous modifications of the invention are contemplated in the appended claims.

I claim:

1. The method which comprises inserting a removable fixture into a casing through an opening therein and thereby defining a space by the exterior walls of said fixture and the interior walls of said casing, sealing said space against substantial leakage, introducing into said space at one or more predetermined locations in the fixture a gaseous suspension of particles of thermal-insulation-forming material which are capable of packing to form a consolidated gas-filtering insulating body thereof and turbulently filling said space with said suspension, simultaneously separating said particles from said gas and venting the gas from said space at one or more predetermined locations in the defining walls of said space until said space is packed with particles in the form of said insulating body, and then withdrawing said fixture from said casing.

2. The method which comprises inserting a removable fixture into a casing through an opening therein and thereby defining a space by the exterior walls of said fixture and the interior walls of said casing, sealing said space against substantial leakage, introducing into said space at one or more predetermined locations a gaseous suspension of particles of thermal-insulation-forming material which are capable of packing to form a consolidated gas-filtering insulating body thereof and turbulently filling said space with said suspension, simultaneously separating said particles from said gas and venting gas from said space at one or more predetermined locations in the walls of said fixture until said space is packed with particles in the form of said insulating body, and then withdrawing said fixture from said casing.

3. The method of insulating a refrigerator which comprises inserting a removable fixture having substantially the size and shape of the inner food compartment into the outer casing of a refrigerator through the door opening of said casing, sealing the intermural space defined by the inner walls of said outer casing and the walls of said fixture against substantial leakage, introducing into said space from one or more openings in the walls of said fixture a gaseous suspension of particles of thermal-insulating-forming material which are capable of packing to form a consolidated gas-filtering insulating body thereof and turbulently filling said space with said suspension, simultaneously separating said particles from said gas and venting gas from said space at one or more predetermined locations in the walls of said fixture until said space is packed with particles in the form of said insulating body, withdrawing the fixture from the outer casing, and mounting in the resulting cavity a food compartment to be insulated by said body.

4. A removable fixture to be confined within a casing for depositing particles of insulating material in said casing and against said fixture as an insulating body, said fixture comprising insulation-confining walls including one or more foraminous areas at predetermined locations acting as filtering means to hold said particles and vent gas, and having one or more openings at predetermined locations for discharging to the exterior of said fixture, and pneumatic conduit means terminating in said one or more discharge openings.

5. A removable fixture to be confined within a casing for depositing particles of insulating material in said casing and against said fixture as an insulating body, said fixture comprising insulation-confining walls including one or more 5 foraminous areas at predetermined locations acting as filtering means to hold said particles and vent gas and having one or more openings at predetermined locations for discharging to the exterior of said fixture, there being at least one 10 insulation-confining wall containing at least one foraminous area and at least one discharge opening, and pneumatic conduit means terminating in said one or more discharge openings.
